UNITED STATES PATENT OFFICE.

WILLIAM B. ROOD, OF WARE, MASSACHUSETTS, ASSIGNOR TO OTIS COMPANY, OF WARE, MASSACHUSETTS, A CORPORATION OF MASSACHUSETTS.

UNDERGARMENT.

Application filed May 11, 1921. Serial No. 468,515.

To all whom it may concern:

Be it known that I, WILLIAM B. Rood, a citizen of the United States, residing at Ware, county of Hampshire, State of Massachusetts, have invented a certain new and useful Improvement in Undergarments, of which the following is a specification, reference being had therein to the accompanying drawings.

10 My invention has for its object a new and improved closure for the seat flaps of union undergarments such as are worn by men, women and children. The object of the present invention is to provide a closure for 15 such undergarments which will tend to hold the seat flaps automatically closed, the movement of the wearer tending to close the seat opening rather than to open it.

In the accompanying drawings, I have 20 shown my invention as embodied in an undergarment of novel form, but I do not claim the said novel undergarment in the present application since the same forms the subject matter of a companion application, 25 filed May 11, 1921 Serial No. 468,514.

The invention will be fully understood from the following description when taken in connection with the accompanying drawings, and the novel features thereof will be 30 pointed out and clearly defined in the claims at the close of this specification.

Referring to the drawings, Fig. 1 is a rear view of an undergarment provided with my invention.

35 Fig. 2 is a view similar to Fig. 1, but showing the edge of the seat flap in the position which it occupies when the edges of the seat opening are pulled apart.

At 11 is shown the body of the undergarment, and at 12 and 13 the outer and inner seat flaps respectively. The upper edge of the outer seat flap is hemmed as shown at *a* and through the hem is run a strap 14 permanently secured at the inner end *b* to the body 40 of the undergarment, and detachably secured at the outer end by the button and button-

hole 15. The button and buttonhole 15 are lower than the point *b* so that the strap slopes downwardly slightly. The free edge *c* of the outer seat flap is so located, as is 50 explained in my said companion application, that the movement of the wearer places a slight strain on this edge and therefore tends to pull the corner *d* of the seat flap downwardly and outwardly along the strap 14, 55 thus holding the seat flap smooth and the seat opening closed. When it is desired to open the seat opening, the hem may be slid toward the median line of the garment, thereby materially increasing the opening, 60 or if desired the strap may be unbuttoned from the button 15. In either case an ample opening is provided and the automatic tendency of the seat flap to keep the seat opening closed is not interfered with. 65

In the accompanying drawings I have shown my novel closure as applied only to the seat flap of a man's union undergarment but it will be understood that I do not limit myself to this use of my invention since 70 other uses will be apparent.

What I claim is:—

1. In combination, a body portion of a union undergarment, a seat flap having a free upper edge, a transverse strap the ends 75 of which are secured to the body of the garment and on which the upper edge of the seat flap is slidable, said strap being located with the end which is at the side of the garment slightly lower than the end which is 80 adjacent the median line of the garment.

2. In combination, a body portion of a union garment, a seat flap having a free upper edge in which is formed a runway for a strap, a transverse strap in said runway having 85 its ends secured to the body of the garment and inclined downwardly toward the end of the strap which is nearest the side of the garment.

In testimony whereof I affix my signature. 90

WILLIAM B. ROOD.
